TEXTILE PACKAGING

Kenneth D. MacColl, Providence, R. I., assignor
to J. & P. Coats (Rhode Island) Incorporated,
Pawtucket, R. I., a Corporation of Rhode
Island

Application May 31, 1930. Serial No. 458,644

3 Claims. (Cl. 206—51)

The present invention relates to the packaging of textile fabrics sold in strip form, and has particular reference to the packaging of tape.

The packaging of these textile articles, particularly bias tape, has heretofore consisted of paper wrappers with the color of the article indicated thereon, or of cellophane wrappers through which the color and texture could be observed. While this latter transparent wrapping is much more satisfactory, it is difficult to match colors accurately and to judge of the texture and the quality of the article, on account of the sheen of the wrapper.

The principal object of this invention is the packaging of a textile article so as to expose a portion thereof outside of the package for direct color matching and for direct observation of the texture and quality of the article.

A further difficulty in the packing of a textile article resides in the necessity for opening the package whenever a purchaser wishes to obtain a sample of the material. A further object of my invention is to provide a packaging construction which will permit the cutting of a sample without necessity for opening or disturbing the wrapping, and without permitting unwinding or unfolding of the textile article.

With these and other objects and advantageous features in view, the invention consists of certain novel arrangements of parts more fully disclosed in the detailed description following, in conjunction with the accompanying drawing, and more particularly specified in the appended claims.

35 In the drawing:

Fig. 1 is a plan view, partly broken away, of a novel packaging for textile articles;

Fig. 2 is a section on the line 2—2 of Figure 1;

Fig. 3 is a plan view of a modified package form; and

Fig. 4 is a detail view of a further modified form.

It has been found desirable to package textile fabrics so as to permit direct inspection of the article and facilitate color matching and examination of the texture and quality. I have therefore devised a package construction which provides a protecting wrapping for the fabric and also provides an opening in the wrapping through which one end portion of the fabric may be extended so as to be positioned outside of the wrapper and accessible for direct inspection; and the following is a detailed description of preferred constructions which embody the principles of my invention.

Referring to the drawing, a textile article such as a bias tape 10 of definite length is wound on a core of cardboard or the like 11. A label band 12, carrying the usual descriptive data, is then placed around the wound tape, and a transparent protecting cover 13 of cellophane or the like is then secured over the package to prevent the soiling of the textile article, and also the unwinding or unfolding thereof.

In order to facilitate direct inspection of the packaged material, an opening 14 through the label and an aligned opening 15 in the cellophane are provided, and one end portion 16 of the textile article is passed through the openings to extend over the cellophane wrapping.

The free end 16 is therefore positioned outside of the package and is available for direct color matching and for direct examination to determine the exact texture and quality of the tape, and if desired, a small portion of this exposed end may be clipped for use as a sample.

Instead of positioning the label band beneath the cellophane, two cellophane end caps 17, 18 may be provided for the package, and a label band 19 may be positioned so as to cover the adjacent edges of the cellophane caps. With this type of packaging, an opening 20 need be made only in the label band, and the free end 21 drawn through this opening. A sticker 22 is preferably used for attaching the free end to the outside of the package, thus tying down the free end and also locking the label band in place without the use of adhesive on the label band.

It is sometimes desirable to position the last layer and the free end of the strip material at one edge of the package, so as to extend over the label band and leave an unobstructed display surface on the label band, as shown in Figure 4. The label band opening 20a is now positioned adjacent the last layer, thus permitting the free end to lie adjacent the edge of the label band. This construction permits a simultaneous view of the exposed end portion of the strip and the printed matter on the face of the label band.

While I have described preferred constructions, such changes in packaging as appear desirable to meet the needs for packaging particular textile articles may obviously be made, within the spirit and the scope of the invention as defined in the appended claims.

I claim:

1. In combination, a folded textile strip, a label band extending transversely of the strip and around said folded strip, and a protecting cover over said label band and said folded strip

to lock the strip against unfolding, said label band and said cover having aligned openings located inwardly from the edges of said band, and said strip having a free end extending through 5 said aligned openings.

2. In a package, a flat core, a strip of textile fabric wound on said core in continuous parallel layers, the last layer terminating adjacent one edge of said core, an envelope of protecting material covering the wound core, said envelope including a label band extending transversely about the strip, said band having an opening intermediate its edges and adjacent the last layer 10

of said fabric, the free end of said fabric extending through said opening and overlying said band.

3. In combination, a package comprising a folded textile strip, a label band embracing the package transversely of said strip and a protecting cover about said package and band, said label band and cover having aligned openings, and said strip having a free end extending through said aligned openings, whereby said label band is held in position relative to said cover. 80 85
